(57) **CLAIM**

The ornamental design of a silverware caddy, as shown and described.

DESCRIPTION

FIG. 1 is a front top perspective view showing the new invention, also showing for illustrative purposes implements in dashed lines that form no part of the claimed design. FIG. 2 is another front top perspective view of the invention from the opposite side as FIG. 1.

FIG. 3 is a front view of the invention with the front and rear views being identical mirror images of each other.

FIG. 4 is a top view of the invention.

FIG. 5 is a bottom view of the invention.

FIG. 6 is a side view of the invention with the left and right side views being identical mirror images of each other.

FIG. 7 is a front top perspective view showing a first alternate embodiment of the invention; and,

FIG. 8 is a front view of the first alternate embodiment with the front and rear views being identical mirror images of each other.

Surface shading has been added in the drawing figures to show the character and contour of the surfaces of the design. The broken lines shown in the figures represent portions of the article that form no part of the claimed design.

1 Claim, 6 Drawing Sheets
